UNITED STATES PATENT OFFICE.

FRANK F. BENTLEY, OF WARREN, OHIO, ASSIGNOR TO THE WARREN AUTOMOBILE CLUB.

DESIGN FOR AN EMBLEM.

49,985.

Specification for Design.

Patented Dec. 5, 1916.

Application filed October 3, 1916. Serial No. 123,592. Term of patent 3½ years.

To all whom it may concern:

Be it known that I, FRANK F. BENTLEY, a citizen of the United States, residing at Warren, in the county of Trumbull and State of Ohio, have invented a new, original, and ornamental Design for an Emblem; and I do hereby declare the following to be a full, clear, and exact description of the same, reference being had to the accompanying drawing, forming a part thereof.

The figure is a plan view of an emblem for use on automobiles, showing my new design.

I claim:

The ornamental design for an emblem, as shown.

In testimony whereof I affix my signature, in presence of two witnesses.

FRANK F. BENTLEY.

Witnesses:

PEGGY BETHUNE,
HARRIET T. UPTON.
